8 Claims. (Cl. 250—41.9)

1

This invention is directed to improvements in methods and apparatus for the analysis of mixtures by mass separation. More particularly the invention is concerned with that phase of mass spectrometry wherein mass separation is accomplished as a function of differences in the periodicity of motion of ions of differing mass-to-charge ratio in a magnetic field.

The principle of mass spectrometry is, in general, one of spatially separating ions produced from a sample to be analyzed as a function of the mass-to-charge ratio of the ions, and selectively collecting the separated ions. Spatial separation of ions of differing mass-to-charge ratio may be accomplished in many ways, usually involving application of magnetic or electrical fields to induce and take advantage of characteristic differences in movement of ions in such fields which differences are a function of their mass-to-charge ratio. A collector electrode may be disposed in space so that under any given set of conditions only ions of a given mass-to-charge ratio will impinge on and discharge at the collector electrode.

It has been found that ions subjected to a magnetic field and an alternating electrical field normal to the magnetic field will move in spiral orbits about an axis parallel to the magnetic field. It is also known that in such crossed fields, ions of differing mass-to-charge ratio will exhibit different and characteristic periods of movement about the axis as a function of the magnetic field strength. Ions of a given mass-to-charge ratio having a periodicity of motion corresponding to the frequency of the alternating field will travel about the axis in orbits of ever increasing radius. These ions are referred to as resonant ions. All ions of mass-to-charge ratio different from the mass-to-charge ratio of the resonant ions will travel about the axis in orbits, the radii of which increase to a maximum, collapse back to the axis and so on in successive cycles. These ions are referred to as non-resonant ions. The non-resonant ions of differing mass-to-charge ratio will travel in different orbits and will attain different maximum radii with those ions most closely approaching the mass-to-charge ratio of the resonant ions attaining the greatest radial displacement from the axis.

By locating a collector electrode at a distance from the axis of rotation exceeding the maximum orbital radius of the non-resonant ions, the resonant ions can be selectively collected and measured. To avoid anomalous ion paths within the field, ions are preferably introduced into the

2

field or are formed at some point along the aforementioned axis. This is conveniently accomplished by projecting an electron beam through the crossed fields parallel to the magnetic field.

5 The electron beam then defines the axis of rotation of the ions.

The designation of ions of any particular mass-to-charge ratio as resonant or non-resonant is relative only to the operation variables, since any

10 change in the magnetic field strength or in the frequency of the alternating field will result in ions of a different mass-to-charge ratio becoming resonant with the alternating field. For this reason, all or any portion of the total mass spectrum of a sample to be analyzed may be scanned by varying the frequency of the alternating field or the strength of the magnetic field so as to bring ions of differing mass-to-charge ratio into resonance with the alternating field.

20 In the practice of this form of mass spectrometry wherein ions are formed along an axial electron beam traversing the crossed magnetic and alternating fields, the number of ions formed varies directly with the cross sectional area of

25 the electron beam. It follows that the sensitivity of the analysis is directly proportional to the cross sectional area of the electron beam. However, increased sensitivity is not readily attained by simply increasing the radius of a more or less uniform beam since to do so would tend to cause ions originating in the center of the beam to have excessive path lengths in reaching a collector means located at the periphery of the fields. As a result of such excessive path lengths,

30 35 ions originating in the center of an ion beam of relatively large radius will have a disproportionately large chance of being lost by gas collision before they are collected. Such loss will, of course, spoil the analytical accuracy of the method.

40 I have now found that the area of the electron beam may be increased to attain the desired high sensitivity without at the same time increasing the probability of ionic collision of any of the ions originating at any place within the beam. To accomplish this, I propose to ionize the gas sample within the region of the crossed magnetic and alternating fields by means of an electron beam in the form of a hollow cylinder. Such a hollow beam may be used without increasing the over-all ionic path lengths and at the expense only of an increased magnetic gap area with a resultant many fold increase in sensitivity.

45 50 55 The invention therefore contemplates in mass spectrometry involving the spatial separation of

ions of a given mass-to-charge ratio in an analyzer region responsive to a magnetic field established across the region, and an alternating electrical field established across the region normal to the magnetic field, and collecting the spatially separated ions of a given mass-to-charge ratio, the improvement comprising introducing a sample to be analyzed into the analyzer region and ionizing the sample by means of a hollow electron beam projected across the region parallel to the magnetic field.

The invention also includes in a mass spectrometer, the combination which comprises an analyzer chamber, means for establishing a magnetic field across the chamber in one direction, means for establishing a high frequency alternating electrical field across the chamber transverse to the magnetic field, means for introducing a sample to be analyzed, means for developing a hollow electron beam and projecting it across the chamber parallel to the magnetic field for ionizing the sample, and a collector electrode disposed in the chamber remote from the electron beam for collecting ions.

To best take advantage of the hollow ionizing electron beam, it is necessary to provide a plurality of collector electrodes spaced around the beam. With this arrangement, ions formed anywhere around the beam will have approximately the same radial distance to travel in reaching a collector electrode.

Any number of means may be employed for developing a hollow electron beam. Although alternative means are illustrated and hereinafter described for accomplishing this, the invention is not primarily directed to the means for developing such a beam but to the combination of such means in a mass spectrometer of a given type.

The invention will be more clearly understood by reference to the following detailed description thereof taken in conjunction with the accompanying drawing wherein:

Fig. 1 is a diagram representing a cross section of an area traversed by a magnetic and alternating electrical field normal to the magnetic field, the section being taken through the magnetic field and showing the conventional type of electron beam paralleling the magnetic field;

Fig. 2 is a similar transverse section through crossed magnetic and electrical fields showing the relationship of the electron beam in accordance with the present invention to such fields;

Fig. 3 is a sectional elevation of one form of apparatus in accordance with the invention;

Fig. 4 is a horizontal section taken on the line 4-4 of Fig. 3;

Fig. 5 is a perspective view of one form of electron gun for developing a hollow electron beam;

Fig. 6 is a section taken on the line 6-6 of Fig. 5; and

Fig. 7 is an elevation of another form of electron gun for developing a hollow electron beam in accordance with the invention.

Fig. 1 is a diagram showing the relationship of a conventional electron beam 10 of radius r_0 to an alternating electrical field represented by an arrow E normal to the axis of the beam and to a magnetic field parallel to the axis of the beam, i. e. perpendicular to the plane of the drawing. A collector electrode 12 is disposed adjacent the periphery of the space traversed by the fields as is conventional in the practice of this form of mass spectrometry. The electrode 12 is spaced at a radius r_3 from the center of beam 10.

The significance of Fig. 1 becomes more apparent upon examination of Fig. 2, which shows a hollow electron beam 14 in accordance with the invention transverse to an alternating electrical field represented by the arrow E and parallel to a magnetic field perpendicular to the plane of the drawing. In this instance, a plurality of collector electrodes 12 are disposed around the beam adjacent the periphery of the crossed fields at a radius r_2 from the center of the beam.

If an electron beam in the form of a hollow cylinder of outer radius r_1 and thickness t of the type shown in Fig. 2 has collector electrodes disposed at a radius r_2 from the axis of the beam, the maximum radial ion path length is equal to the function $(r_2-r_1)+t$. The area of the electron beam which determines the sensitivity 20 of the instrument is given by the expression $\pi[r_1^2-(r_1-t)^2]$, or approximately $2\pi r_1 t$. By keeping t and the function (r_2-r_1) small, ion path lengths may be kept small, not to exceed the maximum radial ion path lengths (r_3) in 25 the system of Fig. 1, while sensitivity may be greatly increased by making the radius r_1 of the electron beam fairly large.

The limits on the radius of the electron beam are determined only by the limits on the cost 30 of developing a magnetic field across the space parallel to the beam, since it follows that the radius r_2 must also be increased along with r_1 in order to achieve a given path length necessary for the spatial separation of resonant from 35 non-resonant ions. In short, there is a minimum value of the function (r_2-r_1) necessary to effective separation. I have found that by using a hollow electron beam of the type shown in Fig. 2, a material increase in sensitivity may be 40 achieved before the attendant increase in magnet cost becomes appreciable. In Figs. 1 and 2 the maximum ionic path lengths [(r_2-r_1) in Fig. 2, and (r_3) in Fig. 1] are the same. However, the sensitivity of an instrument as shown in 45 Fig. 2 is more than six times as great as the sensitivity of an instrument as shown in Fig. 1 at the expense only of an increase in magnetic gap area of about 50%. The advantages of the present invention are apparent from the foregoing discussion.

One form of instrument in accordance with the invention is shown in sectional elevation in Fig. 3 and in horizontal section in Fig. 4, the latter figure being taken on the line 4-4 of 55 Fig. 3. Referring to these figures, the instrument comprises an envelope 20 having magnetic pole pieces 21, 22 forming opposite end walls of the envelope. A pair of semi-cylindrical electrodes 24, 25 are mounted within the envelope 60 and are oriented therein to define a substantially cylindrical analyzer region 26. The electrodes 24, 25 are insulated from each other as by the small gaps separating their adjoining edges. A pair of electrodes 28, 29 are mounted adjacent 65 and across opposite ends of the electrodes 24, 25 substantially enclosing the analyzer region 26. The electrodes 28, 29 are insulated from the semi-cylindrical electrodes 24, 25 as by the illustrated gaps. A number of collector electrodes 70 32 are mounted through the walls of electrodes 24, 25 and are insulated therefrom. The collector electrodes are connected through a common lead to an amplifying and recording network 34 across a grounded resistor 36. The electrodes need not be maintained at ground

potential, the invention having nothing to do with the niceties of potential relationships between the various elements of the instrument.

Envelope 20 is provided with an evacuating line 38 for connection to a vacuum pump (not shown) and with a gas inlet line 40 for admitting a sample of gas to be analyzed into the envelope. Gas entering the envelope through the inlet line 40 finds its way into the analyzer region by diffusion through the gaps separating the four electrodes which define the region.

The end electrodes 28, 29 are provided with substantially centered apertures 28A, 29A respectively, and an electron gun 42 is mounted adjacent the aperture 28A exteriorly of the analyzer region for directing an electron beam 44 through the analyzer region. The beam 44 passes out of the analyzer region through the aperture 29A in the electrode 29 and is discharged at a target electrode 46 located adjacent the aperture 29A exteriorly of the analyzer region 26. Electron gun 42 is of some convenient type for developing a hollow and preferably cylindrical electron beam as shown in the drawing. Various means for producing such an electron beam are illustrated and described hereinafter.

A high frequency oscillator 48 is connected across the semi-cylindrical electrodes 24, 25, and a bias battery 50, connected to the end electrodes 28, 29 and to ground, completes the usual circuit elements.

The operation of the apparatus just described is as follows. The system is evacuated through evacuating line 38 and a sample of gas to be analyzed is admitted to the envelope through inlet line 40. The gas diffuses into the analyzer region 26 and upon intersecting, electron beam 44 will be ionized. Under the influence of the magnetic field and the transverse alternating electrical field established between electrodes 24, 25, the ions will be set in motion with those ions of a mass-to-charge ratio in resonance with the frequency of the alternating field traveling in spiral paths of ever increasing radius until they strike on and discharge at one of the collector electrodes. The ion discharge is amplified and observed and provides means for determining the partial pressure of molecules in the gas sample from which the ions of given mass-to-charge ratio were derived. The non-resonant ions will likewise be set in motion and also in spiral paths, but will spiral outwardly to a maximum radius short of the collector electrode and will thereupon collapse back to the origin (the electron beam) and so forth.

Under the influence of the magnetic field, the ions will tend to drift toward the boundaries of the analyzer region in the direction of the magnetic field. This linear ion drift does not affect the orbital paths of the ions but will interfere with the analysis if the ions are allowed to strike on and discharge at the end walls 28, 29. The small positive bias impressed on the end electrodes 28, 29 by the bias battery 50 prevents such occurrence by repelling ions as they approach these electrodes. The result is that the ions oscillate in the analyzer region parallel to the electron beam while they are driven in their characteristic spiral paths.

The electron gun 42 will emit electrons, but of itself is not capable of propelling the electrons across the chamber. A propelling potential field is necessary for this purpose. This field may be developed by means of an auxiliary electrode interposed between the electron gun and the

apertured electrode. More conveniently the electron gun is operated at a negative potential so that the positively biased apertured electrode will provide the necessary propelling field. This is the arrangement assumed to exist in the drawing (Fig. 3) in which there is no auxiliary propelling electrode.

The operation of the apparatus as just described is in a sense conventional since the hollow electron beam does not affect the spatial separation of the resonant and non-resonant ions nor does it affect the configuration of the motion of these ions. However, as explained above, the hollow electron beam does materially increase the sensitivity of the instrument by providing a greater cross sectional area of ionization without increase in the maximum radial ion path length. Such increase is to be avoided because of the attendant increase in the probability of inter-ionic collisions with a resultant introduction of error. It is for this reason that the same benefits can not be accomplished by increasing the radius of a conventional uniform electron beam.

One means for producing a hollow electron beam is shown in perspective in Fig. 5 and in section in Fig. 6, the latter figure being a section on the line 6-6 of Fig. 5. This means comprises a hot cathode type of electron emitter including a cylindrical cathode 52 having a filament heater 53 disposed therein. To this extent the illustrated electron gun is similar to the electron emitters discussed in Reich, Theory and Application of Electron Tubes, first edition, page 24. The tube 52 has a flat end face 52A on which is disposed an annular layer 54 of an electron emitter such as barium oxide, strontium oxide or the like. Electron tubes having flat end cathodes are known in the art, but to the best of my knowledge the cathodes of all of such tubes are completely covered by a layer of an electron emitter. When the cathode is heated by the filament 53, electrons will be emitted only from the annular coating 54 and in the form of a hollow beam. The beam is maintained in collimation by the magnetic field.

Another means for forming a hollow or tubular electron beam is illustrated in elevation in Fig. 7, which shows a portion of the end electrode 28 (see Fig. 3) with the centered aperture 28A therein. A circular filament 56 is oriented coaxially with respect to the aperture 28A and is of somewhat smaller diameter than the aperture 28A. Electrons emitted from the filament 56 will be directed through the analyzer region of the mass spectrometer in the form of a tubular beam by reason of the circular configuration of the filament, the orientation thereof with respect to the circular aperture 28A, and the collimating action of the magnetic field.

Other means may be developed for producing hollow electron beams now that a purpose for such beams has been discovered. The invention is not intended to be limited to any specific means for accomplishing this. It is in the broader aspects of the use of a hollow electron beam in the practice of mass spectrometry and the combination of means for producing such a beam in a mass spectrometer of the specific type described that the invention is particularly directed.

I claim:

1. In a mass spectrometer, the combination which comprises an analyzer chamber, means 75 for establishing a magnetic field across the

chamber, means for establishing a high frequency alternating electrical field across the chamber transverse to the magnetic field, means for introducing a sample to be analyzed, means for developing a hollow electron beam and projecting it across the chamber parallel to the magnetic field for ionizing the sample, and a collector electrode for collecting ions disposed in the chamber remote from the electron beam.

2. In a mass spectrometer, the combination which comprises an analyzer chamber, means for establishing a magnetic field across the chamber, means for establishing a high frequency alternating electrical field across the chamber transverse to the magnetic field, means for introducing a sample to be analyzed in a substantially un-ionized state, means for developing a hollow electron beam and projecting it across the chamber parallel to the magnetic field and in the plane of symmetry of the electrical field for ionizing the sample, and a collector electrode for collecting ions disposed in the chamber remote from the electron beam.

3. In a mass spectrometer, the combination which comprises an analyzer chamber, means for establishing a magnetic field across the chamber, a first pair of electrodes disposed on opposite sides of the chamber, means including said pair of electrodes for establishing a high frequency alternating electrical field across the chamber transverse to the magnetic field, a second pair of electrodes mounted at opposite ends of said first pair of electrodes and across the ends of the chamber, each of said second pair of electrodes having a substantially centered aperture, means for introducing a sample to be analyzed, an electron gun adapted to develop a hollow electron beam disposed exteriorly of the chamber adjacent the aperture in one of said second pair of electrodes, an electron target disposed exteriorly of the chamber adjacent the aperture in the other one of said second pair of electrodes, whereby a hollow electron beam is projected from the gun to the target across the chamber and parallel to the magnetic field, and a collector electrode disposed in the chamber remote from the electron beam for collecting ions.

4. Apparatus according to claim 3 wherein the electron gun comprises a looped electron emit- 50

ting filament disposed coaxially with respect to said aperture and being of smaller diameter than said aperture.

5. Apparatus according to claim 3 wherein the electron gun comprises a tubular cathode having a flat end face, a heater filament disposed in the cathode for heating said flat end face, and an annular ring of an electron emitting substance coated on said end face.

10 6. In a mass spectrometer, the combination which comprises an analyzer chamber, means for establishing a magnetic field across the chamber in one direction, means for establishing a high frequency alternating electrical field across the chamber transverse to the magnetic field, means for introducing a sample to be analyzed, means for developing a hollow electron beam and projecting it across the chamber parallel to the magnetic field for ionizing the sample, and a plurality of collector electrodes disposed in the chamber remote from the electron beam and oriented around the beam.

25 7. In a mass spectrometer including an ionization chamber, means for establishing a magnetic field across the chamber in one direction, means for establishing an alternating electrical field across the chamber normal to the magnetic field, and a collector electrode, the improvement comprising a gas inlet for admitting a substantially un-ionized gas sample into the chamber for analysis, and means for developing a hollow electron beam and projecting it across the chamber parallel to the magnetic field for ionizing the gas sample.

30 8. In a mass spectrometer, the combination which comprises an analyzer chamber, means for establishing a magnetic field across the chamber, means for establishing a high frequency alternating electrical field across the chamber transverse to the magnetic field, means for introducing a sample to be analyzed, means for developing a hollow electron beam and projecting it across the chamber parallel to the magnetic field for ionizing the sample, and means for collecting ions in the chamber remote from the electron beam.
